UNITED STATES PATENT OFFICE.

CHARLES C. VENABLE, OF PHILADELPHIA, PENNSYLVANIA, ASSIGNOR TO PENNSYLVANIA FORGE COMPANY, OF PHILADELPHIA, PENNSYLVANIA, A CORPORATION OF PENNSYLVANIA.

RING-ROLLING MACHINE.

Application filed October 8, 1924. Serial No. 742,394.

My invention relates to rolling mills and it has particular relation to ring-rolling mills.

One object of my invention is to provide a rolling mill which shall avoid the formation of annular recesses on the several sides of the finished ring.

Another object of my invention is to provide a ring-rolling machine, wherein the several removable parts are readily accessible and adapted to be replaced with a minimum expenditure of time and of money.

A further object of my invention is to provide an improved form of outboard bearing for the mandrel of a ring-rolling machine which shall minimize the frictional wear therebetween.

Other objects and applications of my invention, as well as details of construction and operation, whereby my invention may be practiced, will appear more fully hereinafter, when taken in connection with the accompanying description, claims and drawings, wherein

Fig. 1 is a longitudinal sectional view of a rolling mill embodying my invention;

Fig. 2 is a transverse sectional view taken on the line II—II of Fig. 1, looking toward the left;

Fig. 3 is a view similar to Fig. 2 but looking toward the right, taken on the line III—III of Fig. 1; and

Fig. 4 is an enlarged, detail transverse-sectional view of the outboard bearing, the sectional plane being taken on the line IV—IV of Fig. 1.

In the illustrated form of embodiment of my invention shown in the drawing, a pair of vertically upright standards 1 and 2 having spaced leg portions 3 and 4 are mounted on opposite sides of a central guiding chamber 5 formed in a main supporting frame 6 carried on a concrete base 7.

The spaced legs 3, 4 of the vertical standard 1 terminate at their lower ends in a longitudinally extended base 8 which is provided with a pair of spaced bearings 9 and 11 for a power shaft 12. The base 8 also constitutes an extension off one wall of the guiding chamber 5. The power shaft 12 may be extended beyond the longitudinal extension 8 to provide an end portion 13 which serves as a mounting for gear wheels 14 and 15 and a fly wheel 16. The gear wheel 15

may be actuated from any convenient source of power.

Each leg portion 3, 4 of the vertical standards 1 and 2 is provided with guide surfaces 17 for a vertically movable cross-head 18 which is connected by a piston rod 19 to a power cylinder 21 suitably mounted on a bracket 22 secured to the upper ends of the vertical standards 1 and 2, whereby the cross-head 18 may be raised and lowered in accordance with the operation of the cylinder 21.

Opposite ends of the cross-head 18 are provided with aligned bearings 23 and 24, which may be disposed intermediate the spaced leg portions 3, 4 respectively, and they are adapted to receive a shaft 25 comprising parts 26 and 27. The parts 26 and 27 may be detachably secured together intermediate the bearings 23 and 24 by providing the former with a tapered recess 28 and the latter with a correspondingly formed tapered projection 29. The tapered recess 28 may terminate in a threaded boring 31 for the reception of a screw bolt 32 which extends through an axial perforation 33 in the shaft part 27 to the outer end thereof. A roll 34 may be keyed to the shaft part 26 and rigidly held in position by means of a lock nut 35 mounted on the adjacent end of the shaft part 27.

The shaft part 26 carries a bevel gear-wheel 36 which meshes with a bevel gear-wheel 37 revolvably mounted in a bearing 38 loosely supported on the shaft part 26. The bevel gear-wheel 37 is splined to a vertical shaft 39, an upper end of which is revolvably mounted in a bearing 41 carried by a bracket 42 extending from the upper end of the vertical standard 1. A lower end of the vertical shaft 39 carries a bevel gear-wheel 43 which meshes with a bevel gear-wheel 44 formed on a portion of the power shaft 12 intermediate the bearings 9 and 11. Thus, it is apparent that the bodily movable shaft 25 carrying the roll 34 is continuously in operative engagement with the power shaft 12 regardless of the distance between the same. Moreover, the roll 34 may be conveniently removed from the shaft 25 merely by loosening the lock nut 35 and removing the screw bolt 32 from the threaded boring 31.

A mandrel 45 may be positioned in cooper-

ative relation to the roll 34 in the space intermediate the standards 1 and 2 by extending the end 46 thereof into an adjacent boring 47 in the end of the power shaft 12, and it may be secured in this position by means of a screw bolt 48 which extends axially through a perforation 49 in the power shaft 12 into a threaded boring 51 in the mandrel 45. For purposes of illustration, a 10 particular form of mandrel and pressure roll have been shown with a finished ring 52 in operative engagement therewith but of course these parts may be variously modified.

The sides of the ring 52 may be worked 15 during the rolling operation by means of side pressure rolls 53 and 54, which are vertically positioned in the guiding chamber 5, the former side roll being revolvably mounted in a bracket 55 having an adjustable dove-tail 20 connection 56 (Figs. 1 and 2) with a vertical arm 57 of a supporting member 58. The member 58, which is secured to the main frame 6 and to the base 8, may be provided with a plurality of radially extending arms 25 59 each of which carries an adjustable bracket 61 having a size roll 62 revolvably mounted thereon. In operation, a templet (not shown) having the desired maximum diameter, is mounted in the position occupied 30 by the ring 52 and the several size rolls 62 are then so adjusted as to engage the periphery thereof and clamped in position. Thus a number of rings of any predetermined diameter may be obtained.

35 The side pressure roll 54 may also be mounted in a bracket 63 (Figs. 1 and 3) having a dove-tail connection 64 with a carriage 65 which is disposed intermediate the leg portions 4 of the standard 2 and slidably 40 mounted on spaced ways 66 and 67 formed on the main supporting frame 6, whereby the carriage 65 and hence the side pressure roll 54 may be moved toward and from the ring 52. The movement of the carriage 65 may 45 be further guided by providing spaced shoulders 68 and 69 which are adapted to engage respectively shoulders 71 and 72 formed on the leg portions 4 of the vertical standard 2. The carriage 65 also serves to extend vertically 50 one wall of the guiding chamber 5 as in the case of the base 8.

55 My invention further contemplates the provision of an outboard bearing 73 (Figs. 1, 3 and 4) on the upper side of the movable carriage 65 for the free end of the mandrel 45. The outboard bearing 73 may comprise a sleeve 74 having the opposite ends thereof provided with flanges 75 and 76, the former being disposed in frictional engagement with 60 the pressure roll 34. A washer 77, which is disposed between the ring 52 and the adjacent surface of the flange 75, may have a detachable connection therewith. The frictional contact between the sleeve 74 and the

mandrel 45 may be such as to cause the rotation of the former, whereby any tendency of the mandrel 45 to cut or tear the several parts of the outboard bearing 73 may be avoided. The sleeve 73 may be revolvably mounted in movable supporting members 78 and 79 which are disposed between adjacent vertical side walls 81 and 82 of the movable carriage 65.

In order to compensate for such wear as occurs in the outboard bearing 73, I provide 75 cam blocks 83 and 84, which may be caused to exert a vertical force on the supporting member 79 by means of an adjusting screw 85 extending between the side walls 81 and 82, as will be understood by those skilled in 80 the art.

The carriage 65 may be actuated by means of a cylinder 86, a connecting rod 87 of which is secured to the movable carriage 65 through an adjusting device 88. The latter is designed to provide for small adjustments in the position of the side pressure roll 54 with respect to the coacting pressure roll 53. The operation of the cylinder 86, therefore, may cause the pressure roll 54 to engage the 90 ring 52 with a desired force or it may cause the retraction of the carriage 65 from the position shown in Fig. 1 to such extent that the ring 52 may be readily removed from the mandrel 45 and another inserted in its place. 95

In the experimental development of my invention, some difficulty was experienced due to the failure of the side pressure rolls 53 and 54 to revolve with the ring 52, particularly when the rolls 53 and 54 were of small diameter, but this has been avoided by positively driving the same. To this end, bevel gear-wheels 89 and 91 are mounted on the lower end of the side pressure rolls 53 and 54 in mesh with cooperating bevel gear-wheels 92 and 93, respectively. The bevel gear-wheel 92 may be rigidly secured to a horizontal shaft 94 which is connected by gear-wheels 95 and 96 to the driving gear-wheel 14. In order to provide for the necessary longitudinal movement of the carriage 65, the bevel gear-wheel 93 may be splined to the shaft 94, so that the side pressure roll 54 may be positively actuated at all times regardless of the position of the carriage 65. 115

When a ring is to be rolled, the cylinder 21 is actuated to cause a vertical movement of the shaft 25 to a position where no interference occurs with the mandrel 45. The shaft part 27 is then removed and a roll 34 of desired form is mounted on the shaft part 26, the parts being then clamped in position. The cylinder 86 may also be energized to remove the outboard bearing 73 out of engagement with the mandrel 45 in order that a templet ring may be mounted thereon and the several size rolls 62 adjusted accordingly. Following the removal of the templet

ring, the ring to be finished is placed on the mandrel 45 and the cylinders 21 and 86 actuated to bring the roll 34 and the side pressure roll 54 into working relation with the 5 ring. As the rolling operation progresses, the metal in the ring is so worked as to increase the diameter of the same and, by reason of the circumferential and lateral rolling, a finished ring is finally obtained characterized by the absence of the usual 10 annular recesses.

While I have shown only one form of embodiment of my invention, for the purpose of describing the same and illustrating its 15 principles of construction and operation, it is apparent that various changes and modifications may be made therein without departing from the spirit of my invention, and I desire, therefore, that only such limitations 20 shall be imposed thereon as are indicated in the appended claims or as are demanded by the prior art.

I claim:

1. Apparatus comprising a mandrel, a cooperating pressure roll, a side roll, and means constituting an outboard bearing for said mandrel and a support for said side roll.

2. In combination, a mandrel, a cooperating pressure roll, side rolls, means whereby said side rolls may be positively actuated, and reciprocatory means constituting a bearing for said mandrel and a support for at least one of said side rolls.

3. In a rolling mill, the combination with a pair of cooperating rolls positioned to engage respectively the inner and outer circumference of a ring, of a pair of rolls positioned to engage respectively the sides of 35 said ring, common actuating means for said rolls, and a power operated slide constituting an out-board bearing for one of said first-mentioned pair of rolls and a support for one of said pair of side rolls.

4. A rolling mill comprising a pair of rolls spaced to receive therebetween an element to be operated on, a second pair of rolls so positioned laterally of said first-mentioned pair of rolls as to engage opposite sides of said element, common actuating means for said rolls, and a power operated carriage for bodily moving certain of said rolls and for providing an out-board bearing for one of the remaining rolls.

5. Apparatus comprising a pair of rolls positioned to engage respectively the inner and outer circumference of a ring, a second pair of rolls so positioned as to engage respectively the sides of said ring, and a movable carriage providing a support for one of said rolls and an outboard bearing for another.

6. A rolling mill comprising a pair of spaced rolls for engaging the circumferences 65 of a ring, a second pair of rolls for respec-

tively engaging the sides of said ring, common actuating means for said rolls, and a movable carriage adapted to serve as an outboard bearing for one roll and as a support for another roll.

7. In a ring-rolling machine, the combination with a pair of horizontal rolls positioned to engage respectively the inner and outer circumference of a ring, of a pair of laterally positioned rolls adapted to engage respectively the sides of said ring, means for driving said rolls, means for bodily moving one of said side rolls, said means providing an out-board bearing for one of said horizontal rolls, and size rolls having predetermined positions.

8. In a rolling mill, a pair of angularly positioned rolls, and a power-operated carriage adapted to constitute an outboard bearing for one of said rolls and to support bodily the other of said rolls.

9. A rolling mill comprising a pair of angularly positioned rolls, a power-operated carriage adapted to constitute an outboard bearing for one of said rolls and to support bodily the other of said rolls, and a common power shaft for said rolls.

10. In a ring-rolling machine, the combination with a mandrel and a cooperating pressure roll, of power means for actuating said pressure roll relative to said mandrel, side pressure rolls, power means for actuating one of said side pressure rolls relative to the other and for supporting one end of said mandrel, and a common power shaft for positively driving said rolls.

11. In a rolling mill, the combination with a shaft, of a movable carriage adapted to constitute an out-board bearing therefor, and a roll carried by said carriage, said bearing comprising a revoluble sleeve having a flanged end portion and a washer detachably secured to said flanged end portion.

12. In a ring-rolling machine, the combination with a mandrel, of a cooperating pressure roll, a movable carriage having means constituting an outboard bearing for said mandrel, said means including a revolubly mounted sleeve adapted to be actuated by frictional contact with said mandrel, and a washer interposed between said sleeve and the work.

13. In a ring-rolling machine, the combination with a mandrel, of a cooperating pressure roll, and a movable carriage having means constituting an outboard bearing for said mandrel, said means comprising a revoluble vertically-adjustable sleeve mounted in frictional contact with said mandrel, said sleeve having a flanged end portion for engaging said roll, and a washer interposed between said flanged end portion and the ring to be operated on.

14. In a ring-rolling machine, the combi-

nation with a mandrel, of a cooperating pressure roll, a movable carriage having means constituting an outboard bearing for said mandrel, said means comprising a revoluble 5 vertically-adjustable sleeve mounted in frictional contact with said mandrel, said sleeve having a flanged end portion for engaging said roll, and a washer interposed between said flanged end portion and the ring to be 10 operated on, said washer being detachably secured to said flanged end portion and disposed in frictional contact with said mandrel.

15. A ring-rolling machine comprising a 15 pair of spaced standards, of which one is provided with spaced legs, a vertically-movable cross-head so disposed as to be guided by said standards, said cross-head being provided with bearings, and a pressure roll carried 20 by said bearings and extending between the legs of said standards.

16. A rolling mill comprising a pair of spaced standards, a cross-head movable vertically between said standards, a pressure 25 roll revolvably supported on said cross-head, a cooperating mandrel, and means operatively connecting said mandrel and said pressure roll, whereby an operative connection may be maintained therebetween for all positions of said pressure roll.

30. 17. Apparatus comprising a pair of spaced standards, each standard having vertically positioned legs provided with guiding surfaces, a cross-head disposed intermediate said standards in contact with said guiding surfaces, said cross-head having bearings extending from the opposite sides thereof intermediate the legs of each standard, a pressure roll revolvably mounted in said bearings, a cooperating roll, and a carriage movable intermediate the legs of one of said standards, said carriage being adapted to serve as an outboard bearing for said last-mentioned roll.

45. 18. A ring-rolling machine comprising a pair of spaced standards, each standard having vertically-upright spaced leg portions, a cross-head slidably disposed intermediate said standards in engagement with said leg portions, said cross-head having bearings extending from the opposite ends thereof intermediate the leg portions of each standard, a shaft mounted in said bearing portions and provided with a roll, a cooperating mandrel, the lower portion of one of said standards being formed to provide a support for one end of said mandrel, a carriage for supporting the other end of said mandrel, said carriage being slidably mounted intermediate the leg portions of the other standard, and a side pressure roll revolvably mounted on said movable carriage.

60. 19. A ring-rolling machine comprising a supporting frame, spaced standards mounted on said frame, each standard having

spaced, vertically extending leg portions, a cross-head slidably mounted intermediate said standards, a pressure roll revolvably mounted in bearings formed in said cross-head, one of said standards being formed to provide a bearing, a power shaft mounted in said last-mentioned bearing and terminating in a mandrel positioned in cooperative relation to said pressure roll, means for operatively associating said power shaft and 70 said pressure roll for all positions of the latter, a carriage slidably mounted intermediate the leg portions of the other of said standards, said carriage constituting an outboard bearing for the free end of said mandrel, a side pressure roll mounted on said carriage, and means for operatively associating said power shaft and said side pressure roll.

75. 20. A ring-rolling machine comprising a 85 pair of spaced standards, a movable cross-head so disposed as to be guided by said standards, said cross-head being provided with bearings, and a two-part pressure roll shaft carried by said bearings.

90. 21. A ring-rolling machine comprising a pair of spaced standards, a movable cross-head so disposed as to be guided by said standards, said cross-head being provided with bearings, and a two-part pressure roll 95 shaft carried by said bearings, the ends of said shaft parts being detachably secured intermediate said bearings.

100. 22. A ring-rolling machine comprising a pair of spaced standards, a movable cross-head so disposed as to be guided by said standards, said cross-head being provided with bearings, a two-part pressure roll shaft carried by said bearings, the ends of said shaft parts being detachably secured intermediate said bearings, and a pressure roll 105 mounted on one of said shaft parts.

110. 23. In combination, a pair of rolls, and a power-operated carriage adapted to constitute an outboard bearing for one of the rolls and to support bodily the other of said rolls, said carriage also defining one wall of a guiding chamber.

115. 24. Apparatus comprising a roll, a co-operating bodily movable roll, a carriage constituting one element of a guiding chamber and adapted to provide a journal for the outboard end of said first-mentioned roll, and a side roll positioned in said chamber and bodily movable with said carriage.

120. 25. A roll for engaging the circumference of a member to be treated, means constituting one element of a guiding chamber and adapted to provide a removable outboard bearing for said roll, a roll for engaging the 125 side of said member positioned in said guiding chamber and movable bodily with said means, a movable pressure roll, and means for so operatively associating said last-mentioned roll and said first-mentioned roll that 130

an operative connection may be maintained therebetween for all positions of said pressure roll.

26. Apparatus comprising a pair of spaced standards, of which one is provided with legs, a roll, and a carriage movable intermediate said legs and adapted to serve as a bearing for the outboard end of said roll.

27. Apparatus comprising a pair of spaced standards, of which one is provided with legs, a roll, a carriage movable intermediate said legs and adapted to serve as a bearing for the outboard end of said roll, and a side roll carried by said movable carriage.

28. Apparatus of the class described comprising a standard having a pair of spaced legs, a roll-supporting cross-head, a stationary roll, a carriage constituting an outboard bearing for said stationary roll movable between the legs of said standard, and a side roll carried by said carriage.

29. Apparatus of the class described comprising a standard, a pressure-roll cross-head guided by said standard, a relatively stationary roll, a power-operated carriage constituting one element of a guiding chamber and movable intermediate the legs of said standard, said carriage constituting an outboard bearing for said relatively stationary roll, and a side roll movable with said carriage.

30. Apparatus comprising a pair of spaced standards, each of which is provided with a pair of legs, a roll extending between the legs of one of said standards, a power-operated carriage movable between the legs of the other standard and adapted to constitute an outboard bearing for said roll, and side rolls respectively carried by said carriage and one of said standards.

31. Apparatus comprising a pressure-roll cross-head, a pair of spaced standards constituting a guide therefor, each of said standards having a pair of legs, a roll extending between the legs of one of said standards, the latter standard being formed to provide a journal for said roll, a carriage for supporting the outboard end of said roll and movable between the legs of the other

standard into an ineffective position, and side pressure rolls respectively carried by one of said standards and said carriage.

32. Apparatus comprising a pressure-roll cross-head, a pair of guiding standards therefor, each of said standards having a pair of legs, a relatively stationary roll, one of said standards having a longitudinally extended portion providing a bearing for said roll, a power-operated slide constituting an outboard bearing for said roll and having a path of travel intermediate the legs of the other standard, and side pressure rolls respectively carried by said power-operated slide and said longitudinally extended portion.

33. Apparatus of the class described comprising a standard constituting a guide for a pressure-roll cross-head, said standard having a pair of spaced legs, a relatively stationary roll, said standard also having a base portion providing a bearing for said roll, said base portion serving as one element of a guiding chamber, and a side roll secured to said base portion in said guiding chamber.

34. Apparatus comprising spaced standards, each of which is provided with a pair of legs, a cross-head slidably mounted intermediate said standards, a pressure roll mounted on said cross-head, a stationary roll in co-operative relation to said pressure roll, one of said standards being formed to provide a bearing for said stationary roll, means for operatively associating said stationary roll and said pressure roll for all positions of the latter, a carriage movable intermediate the legs of the other of said standards constituting an outboard bearing for said stationary roll, and a side pressure roll mounted on said carriage.

35. A pair of power-operated carriages disposed in angular relation, a pressure roll carried by one of said carriages, a roll co-operating with said pressure roll, and a side roll carried by the other of said carriages, the latter carriage being adapted to constitute an outboard bearing for said second-mentioned roll.

CHARLES C. VENABLE.
